CLAIM

The ornamental design for a rotary cutter, as shown and described.

DESCRIPTION

FIG. 1 is a top plan view of a rotary cutter showing my new design;

FIG. 2 is a bottom view thereof;

FIG. 3 is a front view thereof, the opposite rear view being mirror image thereof;

FIG. 4 is a left end view thereof;

FIG. 5 is a right end view thereof;

FIG. 6 is a perspective view thereof; and,

FIG. 7 is another perspective view thereof, wherein safety guard member is retracted for cutting operation.

The broken lines shown in the drawings are for illustrative purposes only and form no part of the claimed design.
